DISPENSER FOR POWDERED MATERIAL

Fred R. Richards, Denver, Colo., and Warren G. Richards, Arroyo Grande, Calif.

Application April 28, 1955, Serial No. 35,716

Term of patent 14 years

(Cl. D52—1)

Fig. 2.

Fig. 3.

Fig. 1.

Fig. 4.

Fig. 1 is a front elevational view of a dispenser for powdered material, showing our new design;

Fig. 2 is a top plan view of the dispenser;

Fig. 3 is a side elevational view of the dispenser; and

Fig. 4 is a bottom view of the dispenser.

We claim:

The ornamental design for a dispenser for powdered material, substantially as shown.
